HENRY C. KIHNEMAN, SR., OF MONROE, LOUISIANA

PEDESTAL SUPPORT

Application filed November 22, 1927. Serial No. 235,013.

My invention relates to pedestal supports, and is more particularly concerned with a support of this general type embodying a revoluble top support or table adequately supported, and which while particularly desirable and useful as a support for an electric fan, may be used generally.

An object of the present invention is to provide a pedestal support of this character 10 of simple, rugged construction in which a turn-table top is embodied, this top, in its construction, being adequately supported for rotation by relatively simple and inexpensive means.

15 In the construction of rotatable top surfaces for supports as heretofore proposed, relatively expensive structures and manufacturing operations have been necessary. In the embodiment of a turn-table top support 20 of pedestal type, adequate bracing means supporting the turn-table is necessary to provide a rigid structure. In the present invention, a pedestal support is provided with an adequately braced upper portion presenting a 25 base upon which a turn-table, such as described, is mounted.

These and other features of the invention are described in the following detailed specification when read in conjunction with the 30 accompanying drawings forming part thereof and illustrating a preferable embodiment of the invention.

In these drawings:—

Figure 1 is a perspective view illustrating 35 one embodiment of the pedestal support mounting an electric fan upon its turn-table top.

Figure 2 is a top plan view on an enlarged scale of said top, the fan being removed.

40 Figure 3 is a fragmentary vertical section through the top of the pedestal, this section being taken on the line 3—3 of Figure 2.

In the support of the present invention, provision is made of a vertical standard 1, 45 the lower end 2 of which is carried by a plurality of radiating feet 3 having their supporting terminals 4 substantially spaced from the longitudinal median line of the standard 1 to afford a firm support for the base of the 50 standard which will resist tilting.

The upper portion of the standard 1 which, as shown, is squared is reduced in diameter at its upper extremity to receive a base plate 5 which, as shown, is of circular conformation, but which obviously may be varied in 55 outline if desired. This base plate is centrally apertured to fit snugly over the reduced upper end of the standard 1 and is affixed thereto by any suitable means, as by the screws shown in dotted lines in Figures 60 2 and 3. The upper face of the standard 1 is formed with a circular depression 6 therein presenting an outer annular retaining edge 7 and forming a seat upon which the turn-table rests. It is braced to the standard 1 by means of curved diagonal brace bars 8 having squared lower ends abutting the squared faces 9 of the upper portion of the pedestal below the base 5 and tenoned therein as shown, the upper edges of these brace bars 70 being also squared, and engaging the flat under face of the base 5 adjacent to its outer edges. Screws 10 may be used to attach the upper ends of these brace bars to the base plate 5. Their heads are preferably, as 75 shown, counter-sunk in the upper face of the base 5, so as not to interfere with the revoluble top or turn-table 11 mounted thereover.

This turn-table has its under face formed 80 with an annular flat bearing rib 12 seated in the central recess 6 of the plate 5 with its outer edges adjacent the retaining edge 7 thereof. The portion of the turn-table projecting outwardly beyond the rib 12 extends 85 substantially to the outer edge of the base 5 and is contoured in conformity with the base to present a uniform appearance. This outer edge 13 overlies the securing screws 10 and hides them from view.

90 The table 11 is journaled upon the base 5 by means of a pivoting screw 14 inserted through an opening formed centrally of the table 11 and screwed into the top of the standard 1. The upper end of the screw projects 95 above the top of the standard and fits loosely through the central bore in the table, this bore presenting a cross section similar to that of the upper end of the screw, which has a loose rotatable fit therearound. The 100

pivot bore indicated at 15, Figure 3, permits the flat bevelled head of the screw to be counter-sunk in the base of a shallow concentric recess formed in the upper face of the table 11. This recess 16 receives a metal cover plate 17 having a central bearing socket 18 in its underface alining with the head of the bearing screw 14 and providing for variation in the extent of penetration of the screw into 10 the top of the standard 1. Support of the rotatable top or turn-table 11 upon the base plate 5 is afforded by the annular flat rib 12 of the under face of the table.

It will be observed that all fastening means 15 are covered and that the central cover plate 17, which may be secured to the upper face of the turn table by suitable screws as shown, need only be removed to provide access to the pivot screw and permit the removal of 20 the turn-table top of the pedestal. The upper face of the turn-table is preferably formed with a shallow annular depression 19 bounded by retaining edges 20, the area of the depression being such as to receive the base 25 of that class of articles which the pedestal is intended to take. The base of the electric fan 21, shown in Figure 1, will rest within the central recess 19, for example, with its edges abutting the retaining edge 20. The same would apply to a lamp base, fish bowl or 30 any other article which it is desired to support upon the turn-table. The central recess of the turn-table also provides, in effect, a rotatable tray which may be used for various 35 purposes, independently of its use as a support, such for example, as an ash tray.

From the foregoing it will be understood 40 that the pedestal support with its rotatable top or turn-table is adapted for general use, and that while specifically designed and illustrated as a fan support, its use is not intended to be so limited, and its construction may be varied and adapted in consonance with the spirit of the invention and the scope of the 45 appended claim.

What I claim, therefore, and desire to secure by Letters Patent is:

A pedestal support comprising a fixed standard having a supported base, a table 50 base rigidly attached to the upper end of the standard having its upper face formed with a central circular depression, a removable pivot member extending upwardly above the upper face of the table base in the longitudinal axial line of the standard, a table having a lower portion of reduced diameter to seat within said depression and rotate therein and formed with an annular bearing rib on its under face presenting flat bearing surfaces 55 engaging the face of said depression and retained thereon by the edge bordering said depression, the upper portion of said table extending outwardly beyond the said depression to overlie the outer edge portion of the 60 table base, said table having a bore therein 65

to receive the pivot member and a counter-sunk portion in its upper face to house the upper end thereof, and a removable cover plate for said countersunk portion and pivot member seated on the upper face of the table 70 flush therewith, said upper face being bordered by a retaining ledge for the base of articles resting thereon.

Signed at Monroe in the parish of Ouachita and State of Louisiana this 16th day of November A. D. 1927.
